UNITED STATES PATENT OFFICE

WILLIAM A. CHRYST, OF DAYTON, OHIO, ASSIGNOR TO DELCO-REMY CORPORATION, OF DAYTON, OHIO, A CORPORATION OF DELAWARE

CIRCUIT INTERRUPTER

Application filed November 18, 1927. Serial No. 234,111.

This invention relates to electromagnetically operated circuit make-and-break devices, for example, a reverse current relay for a battery charging system.

5 One of the objects of the invention is to construct at low cost a durable and reliable circuit interrupter and to provide for the ready adjustment of certain of its parts.

Further objects and advantages of the 10 present invention will be apparent from the following description, reference being had to the accompanying drawings, wherein a preferred form of embodiment of the present invention is clearly shown.

15 In the drawings:

Fig. 1 is a plan view of a circuit interrupter embodying the present invention.

Fig. 2 is a side view thereof partly in section.

20 Fig. 3 is an end view looking in the direction of the arrow 3 in Fig. 2.

Fig. 4 is an end view looking in the direction of the arrow 4 in Fig. 2.

25 Fig. 5 is a wiring diagram illustrating the use of the circuit interrupter in a battery charging circuit.

The circuit interrupter includes a magnetizable U-shaped frame 20 which may be readily formed from sheet metal. The yoke 30 21 of the frame is provided with a central aperture for receiving the threaded extension 22 of a magnetizable core 23 having a longitudinal flute formed by a knurling operation. The core 23 is attached to the yoke 35 21 by clamping the yoke by a nut 24 against the core 23. The threaded extension 22 is adapted to extend through a hole in a supporting frame not shown and receives a nut 25 by which the frame 20 is secured to the 40 supporting frame by tightening the nut 25.

The core is surrounded by a main energizing winding 30 of a relatively large number of turns of relatively fine wire and a winding 31 of relatively few turns of heavy 45 wire, which is preferably rectangular in cross section and insulated only by varnish. One terminal 32 of the coil 30 and one terminal 33 of the coil 31 are connected together to a bracket 34 which is attached by rivets 35 to a 50 non-conducting plate 36 carrying contacts

37 which are adapted to be engaged by contacts 38 carried by the blades 39 of a plate 40 of resilient metal such as phosphor bronze. The other end 41 of the coil 31 is located so that it may be attached to a conductor connected with the positive terminal of a generator 80 having its negative terminal grounded. The other end 42 of the coil 30 is attached to a terminal 43 for connection with ground. Thus the main energizing coil 30 is connected across the generator terminals while the coil 31 is connected in series with the interrupter contacts 37 and 38 and will be connected with the positive terminal of a storage battery 81 when the contacts are 65 closed by connection which will now be described.

The contacts 38 are connected by rivets 38a with clips 44 connected by wires 45 with clips 46 which are clamped by screws 47 70 against a hinge supporting plate 48 which in turn is clamped against the frame 20. Thus it is seen that the contacts 38 are electrically connected with the frame 20. The threaded extension 22 of the core 23 not only provides 75 a means for mounting the circuit interrupter but also provides a terminal by which the contact 38 may be connected to the positive terminal of a storage battery. Thus it is seen that when the contacts 37 and 38 are 80 closed, the coil 31 will be connected in series with the storage battery and the generator.

The contacts 37 and 38 are closed electromagnetically when the coil 30 has been energized to a certain degree so that the core 23 85 attracts an armature 50 to which the contact blades 39 are connected by rivets 51. The armature is hingedly connected with the hinge plate 48 by a flexible sheet metal strap 52 attached to the armature 50 by the rivets 90 51 and to the plate 48 by the rivets 53. The armature 50 is urged away from the core 23 so as to maintain the contact 38 out of engagement with the contact 34 by a spring 54 attached at its upper end to an extension 55 of 95 the armature 50 and at its lower end to an extension 56 of an adjustable lever 57 which is pivotally connected with the frame 20 by a stud 58. The plate 57 is provided with a slot 59 for receiving a screw-driver slotted 100

disc 60 having an eccentric shank 61 pivotally attached to the frame 20. By turning the disc 60 with a screw-driver the lever 57 will be turned about its pivot 58 in order to adjust the tension of the spring 54. A screw 62 which passes through a slot 63 in the lever 57 will, when tightened, secure the lever 57 to the frame 20 in the desired position of adjustment.

The armature 50 is limited in its movement away from the core 23 by a stop provided by an angle member 64 attached by a rivet 65 to a non-magnetizable bridge member 66. The angle member 64 has an opening 67 in its upright leg and an extension 68 of the armature 50 passes through this opening and cooperates with the upright leg of the member 64 to limit upward movement of the armature 50 or clockwise movement as viewed in Fig. 2. The member 64 may be bent in order to vary the distance from the stop surface 64a thereof to the bridge 66, and, in this way, to vary the amount of separation of the armature 50 from the core 23.

The bridging member 66 is clamped between the branches of the frame 20 by screws 47 and 70. The screws 70 pass through slots 72 in the non-conducting plate 36, through plain holes in the frame 20 and through threaded holes in the depending leg 73 of the bridge 66. When the screws 70 are loosened the plate 36 may be adjusted longitudinally of the core 23 or vertically as viewed in Fig. 2 in order to vary the amount of contact separation and also to vary the minimum gap between the armature 50 and the core 23. The wires 32 and 33 are sufficiently flexible to permit this adjustment.

The screws 47 pass through slots 75 in the hinge supporting plate 48, through plain holes in the frame 20 and through threaded holes in the depending leg 74 of the bridge 66. By loosening the screws 47, the plate 48 may be adjusted vertically in order to vary the relation of the hinge connection between the armature and plate 48 to the frame 20. In this way the air gap between the armature and core may also be adjusted. Tightening the screws 47 will secure the plate 48 in desired position of adjustment.

All of the adjustments can be readily made by the use of a screw-driver. To vary the tension of the spring 54 the screw-driver is applied to the slotted disc 60 and the screw 62. To vary the maximum air gap between the armature 50 and core 23 the screw-driver is applied to the screws 47, and the stop member 64 may be bent if desired. To adjust the amount of contact separation, the insulating plate 36 may be adjusted by applying a screw-driver in the screw 70.

The invention possesses certain advantages in that the number of parts have been reduced to a minimum by a construction which enables certain parts to perform more than one

function. For example, the bridging member 66 serves to support the stop member 64 and also serves to locate the branches of the frame in definite relation to the core 23 which extends through an opening in the bridging member 66 so as to be definitely located relative to the bridging member. The screws 47 and 70 which clamp the branches of the frame to the legs of the bridging member are used also to secure the contact supporting plate 36 and a hinge bracket 48 in various positions of adjustment relative to the frame 20. The present invention possesses another advantage in that the connection of the interrupter with a battery charging circuit has been facilitated. The threaded shank 22 of the core 23 not only provides for attaching the core to the magnet frame 20 but also provides one of the terminals of the circuit interrupter.

While the form of embodiment of the present invention as herein disclosed, constitutes a preferred form, it is to be understood that other forms might be adopted, all coming within the scope of the claims which follow.

What is claimed is as follows:

1. A circuit interrupter comprising a magnet frame supporting a core surrounded by a winding, an armature pivotally supported by the frame, interrupter contacts, one of which is actuated by the armature, a tension spring for urging the armature away from the core, and means for adjusting the tension of the spring and comprising a lever attached to one end of the spring and pivotally supported by the frame, means for turning the lever, and means for clamping the lever to the frame in adjusted position.

2. A circuit interrupter according to claim 1 in which the pivoted lever is provided with a slot for receiving a screw-driver-slotted disc having an eccentric shank pivotally connected with the frame.

3. A circuit interrupter comprising a U-shaped magnet frame, with parallel sides, a core supported by the yoke of the frame and extending from the yoke in the direction of the frame sides, a non-magnetizable bridge extending from one frame side to the other and having an opening for receiving the free end of the core, screws for attaching the bridge to the frame sides, a pair of interrupter contacts, a bracket attached to one of the frame sides, and supporting one of the contacts, and an armature hingedly connected with the other frame side and supporting the other contact, said screws attaching the bracket and armature hinge as well as the bridge to the frame sides.

4. A circuit interrupter according to claim 3 in which the contact bracket is provided with slots elongated in the direction parallel to the core, said slots receiving the screws which attach one end of the bridge to the frame side, whereby the contact bracket is

adjustable to vary the relation of the stationary contact to the armature.

5. A circuit interrupter according to claim 3 in which the armature is hingedly attached to a bracket clamped against a frame side by 5 screws which attach an end of the bridge to that frame side, the hinge bracket having slots elongated in a direction parallel to the core, said slots receiving said screws whereby the hinge bracket is adjustable to vary the 10 relation of the armature to the core.

6. A circuit interrupter according to claim 3 in which the bridge carries an L-shaped 15 bendable metal member providing an adjustable stop engageable with the armature to variably limit movement of the armature away from the core.

7. A circuit interrupter comprising a U-shaped magnet frame, with parallel sides, a 20 core supported by the yoke of the frame and extending from the yoke in the direction of the frame sides, a non-magnetizable bridge extending from one frame side to the other and having an opening for receiving the free 25 end of the core, a bracket attached to one of the frame sides and supporting an interrupter contact, an armature hingedly connected with the other frame side and supporting another interrupter contact, and means for attaching the bridge and bracket, and the 30 bridge and armature support to the respective frame sides of the magnet, said bracket and armature support being movable relative to the frame sides and bridge member.

8. A circuit interrupter comprising an 35 open ended magnet frame supporting a core surrounded by a winding, each leg of the magnet frame adjustably supporting one contact in cooperative relation with the other, 40 one of said contacts being movable and provided with adjustably resilient means for establishing one circuit condition, and means responsive to the core and windings for establishing the opposite circuit condition.

45. A circuit interrupter comprising a magnet frame supporting a core surrounded by a winding, an armature pivotally supported by the frame, interrupter contacts, one of which is actuated by the armature, means for urging the armature away from the core, and means for varying the effect of the urging 50 means and comprising a lever attached to the urging means and pivotally supported by the frame, means for turning the lever and means for clamping the lever to the frame in 55 adjusted position.

In testimony whereof I hereto affix my signature.

WILLIAM A. CHRYST.
